United States Patent Office

Des. 224,750
Patented Sept. 12, 1972

224,750

CLOCK OR SIMILAR ARTICLE

Theodore G. Daher, Stratford, Conn., assignor to
General Electric Company

Filed June 10, 1971, Ser. No. 152,003

Term of patent 3½ years

Int. Cl. D10—01

U.S. Cl. D42—7

Fig. 1.

Fig. 2.

Fig. 4

Fig. 3

FIG. 6

FIG. 5

FIG. 1 is a front perspective view of a clock showing my new design;

FIG. 2 is a bottom plan view thereof;

FIG. 3 is a front elevational view thereof;

FIG. 4 is a top plan view thereof;

FIG. 5 is a rear elevational view thereof; and

FIG. 6 is a side elevational view thereof.

I claim:

The ornamental design for a clock or similar article, as shown.
